United States Patent Office

Des. 185,334
Patented May 26, 1959

185,334

GAME BOARD OR SIMILAR ARTICLE

Muriel M. Wiebe, Chesterton, Ind.

Application June 20, 1958, Serial No. 51,444

Term of patent 14 years

(Cl. D34—5)

The figure is a top view of the game board or similar article, showing my new design. The game-board is of conventional thickness.

I claim:

The ornamental design for a game board or similar article, as shown and described.
